UNITED STATES PATENT OFFICE.

HERMAN CAMP AND GEORGE W. MCINTOSH, OF ROUSEVILLE, PENNSYLVANIA.

IMPROVEMENT IN THROTTLE-GOVERNORS FOR STEAM-ENGINES.

Specification forming part of Letters Patent No. 119,315, dated September 26, 1871.

To all whom it may concern:

Be it known that we, HERMAN CAMP and GEORGE W. MCINTOSH, both of Rouseville, in the county of Venango and State of Pennsylvania, have invented a certain new and useful Improvement in Throttle-Governor for Steam-Engines; and we do hereby declare that the following is a full, clear, and exact description thereof, reference being had to the accompanying drawing and to the letters of reference marked thereon.

In running steam-engines the motion of the engine is constantly changing on account of the variation of the pressure of steam in the boiler and the varied resistance of the engine. The inconstant draught upon the steam by the engine while in motion, together with the varied resistance to the engine, causes a variation of the steam-pressure in the feed-pipe at every exhaust of the engine, and particularly between the throttle and the piston-head. The object of this invention is to use this varied steam-pressure in combination with the devices hereinafter described for regulating the pressure from the boiler upon the piston-head of the engine, so as to keep the motion of the engine regular and constant irrespective of the steam-pressure in the boiler or the resistance or labor of the engine. The nature of our invention consists in regulating the pressure of steam from the boiler upon the piston-head of the engine by means of a valve which is attached to an arm connected to a piston, which is thrown outward by the steam-pressure and inward by a spring, the inward travel of said piston and the lead of the valve being controlled through the medium of a set-screw, as hereinafter described.

To enable others skilled in the art to make and use our invention, we will proceed to describe more fully its construction and operation.

In the accompanying drawing, which forms part of our specification, Figure 1 is a top view or plan of our improvement in throttle-governor for steam-engines. Fig. 2 is an end view of the same. Fig. 3 is a longitudinal and vertical section at line y of Fig. 1. Fig. 4 is a longitudinal and horizontal section at line y' of Fig. 2. Fig. 5 is a vertical and transverse section at line y'' of Fig. 1.

The accompanying drawing represents a half size of one size of our improvement in throttle-governor.

A represents the shell or casing, in which is fitted a valve, B, to which is attached an arm, C, which is pivoted to a piston, D, provided with a spring, E, the tension of which is regulated by means of the screw-cap F. G represents a set-screw, provided with a jam-nut, h. This set-screw is arranged in the shell or casing A, so that its inner end shall come directly in line with the axis of the piston D and rest against the inner end of the arm C. The end X' of the shell A being attached to the steam-chest of the cylinder of the engine, and the steam-supply pipe leading from the boiler connected with the end X of the shell A, (the steam-pipe leading from the boiler should be provided with a throttle or stop-valve,) the valve B is given sufficient lead through the medium of the set-screw G to admit to the steam-chest enough steam to work the engine when it is unloaded. Now, if the engine requires, say, sixty pounds' pressure of steam in the boiler to work the engine when it is loaded, then a tension is given to the spring E sufficient to hold the piston D against a greater pressure than sixty pounds pressure in the boiler.

All things being constructed and arranged as hereinbefore described, the throttle or stop-valve in the steam-supply pipe is opened to its full extent, the steam enters the chamber J and passes through the opening in valve B, enters the chamber K and presses on the inner end of the piston D, which will cause it to travel outward and thereby move the arm C, which will operate the valve B so as to admit a pressure of steam upon the piston-head of the cylinder sufficient to work the loaded engine and no more. Now, if the engine should suddenly be relieved of her load, the spring E will cause the piston D to be forced inward, which will throw the arm C back against the point of the set-screw G, changing the position of the valve B so as to admit only enough steam to work the unloaded engine.

The skillful engineer will readily understand from the foregoing description that the valve B will be operated through the medium of the arm C, piston D, and spring E, combined with the pressure of steam between the piston-head of the cylinder and the boiler, so that it will control the motion of the engine, keeping it regular and constant in its action irrespective of the steam-pressure in the boiler or labor of the engine.

We do not confine ourselves to any one form of the valve B, for several different forms and

arrangements of said valves may be made and a similar result obtained.

Having thus described the nature, construction, and operation of our improvement, what we claim as of our invention is—

1. The combination of the set-screw G and arm C with the valve B for giving the latter the desired lead, substantially as herein described.
2. The combination, in a throttle-governor, of

the valve B, arm C, piston D, spring E, and set-screw G, constructed and operating with relation to each other substantially as herein described, and for the purpose set forth.

HERMAN CAMP.

GEO. W. McINTOSH.
